UNITED STATES PATENT OFFICE.

JOHN GOOD, OF BROOKLYN, NEW YORK, ASSIGNOR TO GOOD INVENTIONS CO., OF BROOKLYN, NEW YORK, A CORPORATION OF NEW YORK

FUEL-CHARGE-SUPPLY APPARATUS.

1,314,056.

Specification of Letters Patent. Patented Aug. 26, 1919.

Original application filed June 1, 1916, Serial No. 101,017. Divided and this application filed May 23, 1917.
Serial No. 170,413.

To all whom it may concern:

Be it known that I, JOHN GOOD, a citizen of the United States, residing in Brooklyn, New York, N. Y., have invented the following described Improvements in Fuel- Charge-Supply Apparatus.

My invention is concerned with the uniformity of the supply and the character of the combustible mixture of liquid fuel and air supplied to internal combustion engines, particularly automobile and marine engines, and consists essentially in constituting a portion of the length of the suction intake between the engine and the charge-forming device or carbureter, as a Venturi-tube, so that the entire mixture charge must pass through such tube after its measurement in the carbureter, whereby the vaporization of the mixture and its homogeneity are greatly improved, with corresponding improvement in the engine efficiency, and whereby also the liquid fuel to form the mixture may be brought from a storage tank at a lower level to a local service tank at a higher level, from which it may flow by gravity and under substantially constant head to the carbureting spray nozzle thereby assuring constant conditions for the formation of the mixture. The improvement in the combustibility of the charge mixture results from the combination of the two conditions of high velocity and sharp pressure reduction occurring at the throat of the Venturi-tube accompanied also by the deposition of the liquid spray on the wall of the tube as it passes through, and the consequent film-vaporizing action that occurs in such passage. It is necessary for this purpose that substantially the entire charge, in the form of a previously formed spray, enter the convergent entrance of the Venturi-tube. In the accomplishment of the uniformity of liquid supply, the invention consists in the combination of the same Venturi-tube with a local service tank having suitable automatic controlling agencies whereby the pressure depression existing at the throat of the venturi is caused to supplement the normal relative vacuum in the suction intake and create vigorous liquid flow to said local tank from the main supply at a lower level under all conditions of use and independently of the adjustment of the engine throttle. Local service supply tanks of this kind, operated

by the relative vacuum in the suction intake are already well known to the art and I prefer to employ my present invention with that type of local service tank shown and described for example in the patent to Webb Jay No. 1,158,924, dated November 2, 1915. Such apparatus is provided with the usual double chamber construction, a float valve, and suitable pipe connections to the suction intake and the main supply tank and, under the control of the float valve, operates intermittently to allow the vacuum in the suction intake to draw the liquid fuel from the main tank into the upper chamber of the local tank from whence it flows into the lower chamber and thence to the carbureter spray nozzle. In such apparatus, as now and heretofore used, vacuum conditions normally existing in the suction intake depend principally upon the position of the engine throttle which controls the flow therethrough, a closed throttle creating a very considerable relative vacuum. When the throttle is full open, or nearly full open, however, the relative vacuum in the suction intake is, of course, very much less and is too slight of itself to effect the desired suction operation and such reduced suction frequently coincides with working conditions requiring the maximum fuel supply, that is to say, maximum fuel is needed when the throttle is wide open, so that the fuel is thus apt to fail when most needed. This objection is not apparent in automobiles where the throttle is seldom full-open and never full open for very long periods, and where the capacity of the local tank is made large enough to accommodate the maximum expected full open operation, but in marine engines where a wide open throttle is the normal position the said apparatus cannot be practically used for obvious reasons, and even with liberal tank capacity are uncertain of operation for automobiles under certain conditions, such for example as when the loaded engine with wide open throttle is ascending a very long hill. By the present invention the minimum degree of relative vacuum available to lift the fuel is always sufficient for the purpose whether the throttle is wide open or not and the increased vacuum is obtained not only without imposing any appreciable restriction to the flow of the charge mixture to the engine but ac-

tually improving the character of the mixture so that it is capable of more efficient combustion and thereby the utility of apparatus of the kind referred to and the engine plant as a whole is materially increased, and the utility of the said apparatus is extended to fields in which it has not heretofore been available, to wit, motor-boats and conversely smaller local tanks may be used 10 in automobile service with the same or better results than heretofore.

In the accompanying drawings I have shown such a service tank as above referred to and as shown in the said patent of Webb 15 Jay combined with a Venturi tube constituting part of the suction intake manifold of an engine in accordance with my invention. Figure 1 being the general organization, and Fig. 2 being a modified form.

The engine illustrated in outline may be assumed to be an ordinary automobile engine having a suction intake manifold 1 connected with a carbureter 2 of any desired or suitable type by means of a Venturi tube 3. This tube comprises a relatively abruptly convergent entrance section 4 and a longer divergent recovery portion 5 the widest diameter of each section being equal to the general diameter of the suction intake passage as a whole. The taper of both sections is determined according to the known principles of Venturi tube construction, with reference to the normal flow through the engine intake and to produce a local region of sharp pressure reduction at its throat or narrowest point without however producing any appreciable obstruction to flow by reason of the narrow diameter at the throat, and that being the characteristic of 40 Venturi-tubes as distinguished from other constricted passages. The local reduction of pressure at the throat is accompanied by corresponding local increase of the flow velocity and these two coincident conditions 45 are conducive to rapid and complete vaporization of the liquid fuel in the air and thorough mixing of the vapor therewith. It is to be noted that the mixture of the liquid fuel and air is formed by and within 50 the carbureter 2 which has the usual spray valve nozzle 6 for that purpose, so that a previously formed spray mixture enters the Venturi tube, and is directed against the convergent wall surfaces of the entrance section 4. The suspended liquid thereby forms a film on the said surfaces subject to the friction of the gaseous flow and in consequence becomes more completely and homogeneously vaporized. The entire engine 60 charge is thus passed through the Venturi tube, and the vacuum occurring at the throat serves not only to facilitate vaporization but also to operate the liquid supply apparatus as above stated. Such 65 vacuum depends upon the velocity of the

flow through the Venturi, but the flow with wide open throttle and the engine under load is ample to give an adequate vacuum effect to lift the fuel to even greater elevations than normally required, this being due 70 to the known characteristics of the Venturi tube and without imposing any appreciable restriction to flow through the intake. The vacuum effect due to partial closing of the throttle is supplemental to and not the controlling factor of the suction acting to lift the fuel.

The liquid receptacle of the carbureter 2 is kept at a constant level in Fig. 1 by means of the usual float controlled valve as indicated, and receives its liquid through a pipe 7 from the local service tank 8 mounted at a higher level. This tank in turn receives its supply of liquid fuel through the pipe 9 from a main storage tank 10 which is to 80 be understood as the tank commonly attached to the rear of the automobile at about the level of the rear axle, and hence below the level both of the local tank 8 as well as below the carbureter. The construction and 85 mode of operation of the local tank shown is the same as that shown and described for example in the patent above referred to and to which reference may be had for a further and detailed explanation thereof. Briefly, the said tank includes an upper and a lower chamber for the liquid fuel and the upper chamber is in constant communication with the storage tank through the supply line 9 and is adapted to discharge its liquid into 100 the lower chamber through a flap-valve outlet 24. Suitably guided in the upper chamber there is a float 19 connected to and operating a lever 20, and through a link 21 this lever operates a second lever 22 to which a spring or springs 23 is connected and the other end of the spring is connected to a short lever 18, the arrangement of the two levers being so related to their common fulcrum that as the float rises and falls the spring is carried past the axis of the fulcrum thereby resulting in a snap movement of the short lever 18. The latter lever 18 operates two valves; one of them, 16, 110 controls the communication between the upper chamber and the suction pipe 11 and the other 17, controls a communication between the upper chamber and the vent to atmosphere, 15. The suction pipe 11 leads to the throat or point of narrowest constriction of the Venturi tube 3 above described and is therefore subject to the local pressure depression always existing at that point. The falling of the float 19, which results from the discharge of the liquid 115 therein into the lower chamber, simultaneously closes the air vent 17 and opens communication through the pipe 11 with the Venturi tube and thereby the relative vacuum of the latter is extended into the upper 120 125 130

chamber causing immediate flow of liquid fuel to that chamber against gravity from the storage tank 10. This flow continues until the float 19 shifts the spring 23 past the fulcrum of levers 22 and 18 whereupon the suction valve 16 is closed and the air vent valve 17 is opened thereby permitting the liquid just drawn into the upper chamber to flow by gravity into the lower chamber and presently reaching a condition where the movement of the float valve takes place in accordance with the withdrawal of fuel from the lower chamber to the carburetor, that is to say, in accordance with the demands of the engine. The lower chamber will be observed also to be in communication with atmosphere through the vent 15.

The throttle 12 is interposed between the Venturi tube and the carburetor 2 so that the whole charge as formed in the latter is admitted to the Venturi tube according to the throttle adjustment.

Any type of carburetor may be used, and in Fig. 2 I have shown a modified form of the same type shown in Fig. 1, but wherein the liquid level of the receptacle is kept at a predetermined height by means of an overflow circulation system, the overflow returning back to the main storage tank 10. The liquid feed pipe 7, having the same connection to tank 8 as above described, delivers the liquid into the compartment 30 with a constant delivery exceeding the maximum requirement of the engine and the spray nozzle 6 takes its liquid from this chamber. The excess overflowing the upper edge of the wall of the compartment 30 into the surrounding compartment 31, flows back to the tank by the return pipe 32. By this arrangement a continual circulation of the liquid fuel is established, while the engine is in operation, and the fuel in the main storage tank is thereby kept in motion, which has the effect of keeping it of a constant quality and specific gravity throughout, by preventing gravitational separation or stratification of the components. When lubricating oil is added to the fuel, this circulation has the effect of maintaining a homogeneous mixture therein with the fuel.

From the foregoing it will thus be apparent that the invention provides for the general improvement of the means for supplying the combustible to internal combus-

tion engines and it remains to point out that it applies equally to all kinds of fuel, as will be evident. When using fuels heavier than gasolene, heat is applied to the fuel within the Venturi tube to thereby supplement its natural vaporizing action, the heat being taken from the water-jacket of the engine or its exhaust gases, according to prior art methods and the character of fuel used, and such heat may be applied to the exterior of the tube or to the air entering the same, or both, as preferred.

This application is a division of my pending application Serial No. 101017, filed June 1, 1916.

I claim:

1. The combination with an internal combustion engine, of means for supplying combustible thereto comprising a local service tank, a charge-forming device supplied thereby, a Venturi tube interposed between and connecting said device with the engine, and a suction pipe connected to the throat of said Venturi tube and adapted to communicate the suction effect therein to said tank to fill the same with fuel.

2. The combination with an internal combustion engine, of means for supplying combustible mixture thereto, comprising a charge-forming device, a Venturi-tube constituting part of the length of the suction intake between said device and the engine, a throttle intervening between said device and Venturi tube, a local service tank to supply said device, and a suction pipe connected with the throat of the Venturi tube adapted to extend the suction effect in said intake to said local tank to fill the same with fuel.

3. In an internal combustion engine the combination of a pipe or passage connected to the engine and including a section of its length constituted by a Venturi tube, a throttle placed in advance of and controlling the flow to said tube, a local service tank, and a suction pipe connected to the throat of the Venturi tube and adapted to communicate the suction effect thereof to said local tank to fill the same with fuel against gravity.

In testimony whereof, I have signed this specification.

JOHN GOOD.
